DESIGN FOR A BOTTLE

Whryosley F. Jackson, Greenville, N. C.

Application October 13, 1941, Serial No. 103,756

Term of patent 14 years

To all whom it may concern:

Be it known that I, Whryosley F. Jackson, a citizen of the United States of America, residing at Greenville, county of Pitt, and State of North Carolina, have invented a new, original, and ornamental Design for a Bottle, of which the following is a specification, reference being had to the accompanying drawing, forming a part thereof, wherein:

I claim:

The ornamental design for a bottle, as shown.

WHRYOSLEY F. JACKSON.
